CLAIM

The ornamental design for a power shovel as shown and described.

DESCRIPTION

FIG. 1 is a first perspective view of a power shovel showing our new design;

FIG. 2 is a second perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged left side view thereof; and,

FIG. 10 is an enlarged right side view thereof.

The portions of the power shovel shown in broken lines form no part of the claimed design.
